Primary Examiner — Keli L Hill*(74) Attorney, Agent, or Firm* — Danielson Legal LLC**CLAIM**

The ornamental design for a beverage container, as shown and described.

DESCRIPTION

FIG. 1 is a perspective view of the beverage container of the present invention;

FIG. 2 shows the beverage container of FIG. 1, with the beverage container depicted in a side view; and,

FIG. 3 shows the beverage container of FIG. 1, with the beverage container depicted in a top view.

The horizontal broken line comprising a pattern of dot dot dash represents a border between portions of the article that form a part of the claim and portions of the article that form no part of the claim.

The broken lines and dotted texture represent portions of the article that form no part of the claim.
